UNITED STATES PATENT OFFICE.

MILO BAXTER RUNYAN, OF FORT BUFORD, DAKOTA TERRITORY, ASSIGNOR
TO HIMSELF AND BLANTON C. WELSH, U. S. A.

WHIFFLETREE-COUPING.

SPECIFICATION forming part of Letters Patent No. 372,988, dated November 8, 1887.

Application filed July 28, 1887. Serial No. 245,540. (No model.)

To all whom it may concern:

Be it known that I, MILO BAXTER RUNYAN, a citizen of the United States, residing at Fort Buford, in the county of Buford and Territory of Dakota, have invented certain new and useful Improvements in Whiffletree Couplings, of which the following is a specification.

This invention relates to a whiffletree-coupling for connecting either a singletree, a doubletree, or a trebletree to a vehicle-pole.

The object of the invention is to provide a safety whiffletree-coupling in which the "wagon-hammer" or pivot-bolt will be locked against accidental displacement, and in which the whiffletree will be retained in position in case the pivot-bolt should break.

Figure 1 of the accompanying drawings is a perspective view of this improved whiffletree-coupling. Fig. 2 represents a vehicle-pole and a whiffletree connected by this improved coupling. Fig. 3 is a view, partly in section, on line 3 3 of Fig. 2. Fig. 4 is a section on line 4 4 of Fig. 2.

Similar numerals of reference indicate corresponding parts in the different figures.

The vehicle-pole 5 and the whiffletree 6 are of any ordinary construction. The coupling for connecting these parts comprises a plate, 7, attached to the pole, a bow or strap, 8, detachably connected to the plate 7, and a spindle, 9, having its bearings in said strap and plate and passing through the whiffletree.

The plate 7 is provided with holes 10, through which bolts or screws 11 are passed for attaching it to the vehicle-pole, and preferably at its rear end with a rabbet, 12, the rabbed end lapping under the ordinary T-iron, 13, used to strengthen the joint between the pole proper and its cross-bar. This plate 7 has a socket or step-bearing, 14, near its center, for the lower end of the spindle 9, perforated ears 15, near its front end, recessed ears 16, near its rear end, and a slot, 17, between the ears. The central portion of the plate 45 having the socket 14 is increased in breadth by flanges 18, so that the plate will not be weakened by the socket. A raised annular rib, 19, surrounds the socket-hole 14 on the plate 7.

The strap 8, which takes the place of the ordinary "hammer-strap," is elongated into the form of a bow and is provided at one end with an eye, 20, which fits between the perforated ears 15, and a bolt, 21, passed through said ears and eye, serves to fasten the front end 55 of said strap to the plate 7. The bolt 21 is provided with a slot, 22, through which an ordinary or spring key, 31, is passed for retaining the bolt in its place. The strap 8 is provided at its rear end with a T-shaped 6c tongue, 23, which interlocks with the recessed ears 16 of the plate 7. This strap is also provided about the center of its length, opposite the socket 14 of the plate 7, with a socket, 24, for the upper end of the spindle 9.

The body of the spindle 9, which takes the place of the ordinary wagon-hammer, is preferably angular or square in cross-section, and is provided at its opposite ends with journals or pivots 25 26, which have their bearings in the sockets 14 and 24, respectively, of the plate 7 and strap 8. The pivots being smaller in diameter than the body of the spindle, a shoulder, 27, is formed between the body of the spindle and the upper pivot, 25, which 75 shoulder, coming in contact with the strap 8, prevents the spindle from being thrown or jarred upward out of place. This spindle is also provided with a flange, 28, at the lower end of its body above the lower pivot, which 80 flange rests on the rib 19 around the socket 14. The spindle 9 is passed through the whiffletree, and the flange 28 is provided with screw-holes 29, by which the spindle is securely fastened to the whiffletree.

In assembling the parts the spindle 9 is passed through and secured to the whiffletree. The strap 8 is turned at right angles to the plate 7, and the T-shaped tongue 23 is passed down between the recessed ears 16 and through 90 the slot 17 into the slot 30 in the body of the pole until the cross-bar of the tongue is below the body of the plate. The strap is then turned into a position in line with the plate and the T-shaped tongue raised into the recesses in the ears 16, the strap being then in the position shown in dotted lines in Fig. 2. The whiffletree in which is inserted the spin-

dle 9 is then passed under the strap 8 and the pivot 25 of said spindle inserted in the socket 24 of the strap. The whiffletree and strap are then lowered and the pivot 26 of the spindle 5 inserted in the socket 14 of the plate and the eye 20 of the strap passed between the perforated ears 15 of the plate and secured in position by the bolt 21.

When the parts are separated, the whiffletree 10 is preferably raised with the strap to avoid binding.

In this improved coupling the wagon hammer is locked in position against accidental displacement, and it serves to brace the hammer-strap. 15

I claim—

1. The combination of the plate for attachment to the pole, provided with recessed ears and a slot at one end, perforated ears at the 20 opposite end, and an intermediate socket, a bow-shaped strap having a T-shaped tongue at one end, an eye at the other, and an intermediate socket, and a spindle for the whiffletree, provided with reduced pivots at its opposite ends having their bearings in said sockets, substantially as described. 25

2. The combination of the plate for attachment to the pole, provided with recessed ears and a slot at one end, perforated ears at the

opposite end, and an intermediate socket, a 30 bow-shaped strap having a T-shaped tongue at one end, an eye at the other, and an intermediate socket, and a spindle for the whiffletree, provided with reduced pivots at its opposite ends having their bearings in said sockets, 35 said spindle having a flange for attachment to the whiffletree, substantially as described.

3. The combination, with a pole-plate and strap, of a whiffletree-spindle having pivots 40 at its opposite ends, and a flange integral with the spindle for attaching the latter to the whiffletree, substantially as described.

4. The combination, with a pole-plate provided with an elongated slot and with outwardly-projecting ears on opposite sides of said slot, said ears having recesses open at the inside of the plate, of a strap provided at one end with a T-shaped tongue which is passed through said elongated slot and into said recesses for engaging said ears, and means for connecting the opposite end of said strap to the pole-plate, substantially as described. 45 50

MILO BAXTER RUNYAN.
